UNITED STATES PATENT OFFICE.

ELMER GEO. DARY AND ARTHUR PHINEAS CLUTE, OF QUINCY, ILLINOIS.

MECHANISM FOR PROPELLING VESSELS.

Application filed March 31, 1922. Serial No. 548,456.

To all whom it may concern:

Be it known that we, ELMER G. DARY and ARTHUR P. CLUTE, citizens of the United States, residing at Quincy, in the county of 5 Adams and State of Illinois, have invented new and useful Improvements in Mechanism for Propelling Vessels, of which the following is a specification.

This invention relates to mechanism for propelling vessels, and the object is to provide an endless travelling element on each side of the vessel, said element including buckets or other propelling means and being so mounted that the draft required will not 10 exceed that required for the vessel itself, as distinguished from those types of side wheel and stern propelled vessels requiring a much greater draft, by reason of the propelling mechanism than is required for the vessel 15 alone.

A further object is to provide propelling mechanism adapted to be constructed in units, each unit being separately mounted and separately driven, so that in the event 20 of temporary repairs being required, one or more units may be raised from the water and the necessary repairs effected, while the vessel is still proceeding on its course under the power derived from the remaining propelling units.

A still further object is to provide a ship, boat, or barge with an endless propelling device or devices which shall be mounted in frames movable bodily in a vertical direction, and to provide an adjustable drive between the wheels mounting the endless device and the power shaft and chain belt.

With the foregoing and other objects in view, the invention consists in the novel construction and arrangement of elements described and claimed, it being understood that modifications may be made within the scope of the claims without departing from the spirit of invention.

In the drawings, Figure 1 shows the mechanism in side elevation;

Figure 2 is an end elevation;

Figure 3 is a horizontal section of one of the vertical guides and the element movable 50 therein;

Figure 4 is a similar view of a shaft guiding element;

Figure 5 is a plan view of a portion of the propelling chain;

Figure 6 is a vertical section of one of the 55 propelling elements or links of the propelling chain;

Figure 7 shows a modified drive employing an electric motor 61 for driving the 60 shaft 60.

In carrying out the invention, we provide for each unit, a pair of vertical guides 10 and 12 and secure them in any suitable manner to the sides of the vessel. These guides may be of channel iron or steel, and 65 cooperating therewith are the slidible elements or blocks 13 and 14 mounted respectively in the end portions of the longitudinal element 15. This element last named is also of channel iron or steel, the flanges 70 being outwardly turned, and a timber 16 being bolted therebetween.

Channels 17 and 18 are also secured in vertical position on the sides of the vessel and within the guides formed by the channels, we provide for mounting the frames 75 19 and 20 in which the wheels 21 and 22 for the endless propelling device 23 are mounted. The shoes 24 and 25 serve to directly co-operate with guides 17 and 18, and it should 80 be stated that these guides, and guides 10 and 12 have their flanges inwardly turned at their outer edges.

The frames 19 and 20 include upper transverse members, such as 25, and vertically 85 extending elements 26 mounting pulley blocks 27. A cable 28 passes around this pulley and also around a pulley 29 suspended from an outwardly extending arm 30, suitably mounted on the sides of the vessel. This arrangement permits of the elevation 90 of the frames mounting the endless devices. In the case of small vessels, only one endless device 23 may be needed on each side, but several independent propelling units 95 may be employed for vessels of greater size.

The endless propelling device 23 includes individual propelling devices or members, which may be termed buckets or paddles. The devices are of sheet steel, are wedge 100

shaped in cross section and include side portions 32 and 33, inclined with reference to each other, adjacent devices being connected by short bars or links 35. These elements 5 last named are provided with eyes 36 through which the transverse rods or shafts 37 pass. On opposite ends of shafts 37 are wheels, such as at 38, for cooperation with the channeled guides 40 and 41, supported by 10 the frames 19 and 20. These frames being vertically movable, the entire propelling units including the endless device 23 moves vertically at one side. The wedge shaped propelling devices may be termed links of a 15 chain propeller.

A main drive shaft 44 carries a double sprocket wheel 45, one element of which drives a main chain belt 46 imparting movement to a double sprocket wheel 47.

20 The shoes 24, 25, previously referred to, may be mounted directly on shafts 48 and 49, these shafts mounting wheels 21 and 22, and rigid with reference to these wheels and shafts just named are sprocket wheels 51 and 25 52 through which the endless propelling device 23 is driven, it being understood that the drive is primarily through wheel 21. Sprocket wheel 51 is driven by chain 53 passing around the double sprocket wheel 30 54, mounted as shown. One element of this sprocket wheel is driven by chain 55, which in turn is driven from one element of double sprocket wheel 45. Chain 55 also passes around the sprocket wheels 56 and 57 mounted 35 on a spreading device 58, comprising a plurality of pivoted elements 59 adapted to automatically take up the slack in chain 55 due to the difference in the distance between the axes of sprocket wheels 44 and 54, at 40 different times, depending upon the position or elevation of the endless device 23. A similar arrangement is provided in connection with the drive for sprocket wheel 52, and wheel 22. Wheel 47 is not however 45 driven from the motor, but from the main chain belt 46.

In the form shown in Figure 7, the chain tightening device including elements 58 and the sprocket wheels carried thereby are 50 omitted, and shaft 60 mounting sprocket wheel 54', is driven directly from an electric motor 61 mounted on one of the vertically movable frames. The drive to the other side of the endless propelling device is 55 then through sprocket chain 55', sprocket wheel 45 and main chain belt 46. On certain classes of vessels, no provision need be made for elevating the endless device 23, thus simplifying the construction to a considerable degree.

Having thus described the invention, what we claim is:

1. In a device of the class described, an endless propelling element, means for mount-

ing the same for vertical adjustment, at the 65 side of a vessel, and means for imparting movement to the endless element, said means last named including a plurality of pairs of sprocket wheels, one of the wheels of each pair being movable toward and away from 70 the other wheel of that pair, and chains connecting the wheels of corresponding pairs.

2. In a device of the class described, an endless propelling element, means including a plurality of vertically movable frames for 75 mounting the propelling element at the side of a vessel, and means for imparting movement to the endless element, said means last named including a plurality of pairs of sprocket wheels, one of the wheels of each 80 pair being movable toward and away from the other wheel of that pair, and chains connecting the wheels of corresponding pairs.

3. In a device of the class described, an 85 endless propelling element, an endless drive chain mounted adjacent thereto, means for mounting the element at the side of a vessel, and permitting vertical movement, and means providing a continuous drive for the 90 endless element from said drive chain, independent of the elevation of the endless element, said means last named including chains and idlers for the chains, the idlers, being movable toward and away from each other.

4. In a device of the class described, a plurality of vertical guides mounted at the side of a vessel, frames movable in said guides, an endless propelling element, wheels mounted in the frames, and mounting the 100 endless element, and means for driving the wheels, additional vertical guides, shafts extending transversely of the endless elements and shoes carried by the shafts and movable in the vertical guides last named.

5. In a device of the class described, a plurality of vertical guides mounted at the side of a vessel, frames movable in said guides, an endless propelling element, wheels mounted in the frames, and mounting the 110 endless element, and means for driving the wheels, said driving means including a main drive chain and supplementary drive chains, means for automatically tensioning some of the chains last named, and gearing driven 115 from the main chain.

6. In a device of the class described, a plurality of vertical guides mounted at the side of a vessel, frames movable in said guides, an endless propelling element, wheels 120 mounted in the frames, and mounting the endless element, and means for driving the wheels, shafts for mounting the wheels, and shoes carried by the shafts and cooperating with some of guides.

7. In a device of the class described, a plurality of vertical guides mounted at the side of a vessel, frames movable in said guides,

an endless propelling element, wheels mounted in the frames, and mounting the endless element, and means for driving the wheels, said driving means including a main drive

5 chain, sprocket wheels mounting said chain, supplementary chains and additional sprocket wheels driven thereby, adjustable tightening means associated with the supplementary chain, and means imparting motion to the

wheels first named from said additional ¹⁰ sprocket wheels.

In testimony whereof we affix our signatures.
